(57) **CLAIM**

The ornamental design for automobile tire, as shown and
described.

DESCRIPTION

FIG. 1 is a front view of an automobile tire, showing the new
design, a rear view thereof, a top plan view thereof and a
bottom plan view thereof appearing the same as the front
view;

FIG. 2 is a right side view of the automobile tire, a left side
view thereof appearing the same as the right side view;

FIG. 3 is a fragmentary front view, showing in enlargement
the portion of 3—3 in FIG. 1;

FIG. 4 is a cross-sectional view, taken along line 4—4 and
in the direction of arrows in FIG. 3; and,

FIG. 5 is a perspective view of the automobile tire.

The broken line showing of a tire sidewall, inner bead and
peripheral boundary between the tire tread and sidewall is
for illustrative purposes only and forms no part of the
claimed design.
